(57) **CLAIM**

The ornamental design for a clock, as shown and described.

DESCRIPTION

FIG. 1 is a front perspective view of a clock according to my new design, illustrating a cloth grill;

FIG. 2 is a front view of the design of FIG. 1;

FIG. 3 is a rear view of the design of FIG. 1;

FIG. 4 is a right side view of the design of FIG. 1, the left-side view being a mirror image thereof;

FIG. 5 is a top view of the design of FIG. 1; and,

FIG. 6 is a bottom view of the design of FIG. 1.

The broken lines depict parts of the clock that form no part of the claimed design.

Conventional contour lines and shading are illustrated for purposes of highlighting the solid-rendering, but form no part of the claimed design.
